UNITED STATES PATENT OFFICE.

JOHN F. HUNT, OF MALDEN, MASSACHUSETTS.

DISINFECTING APPARATUS.

1,210,650.

Specification of Letters Patent. Patented Jan. 2, 1917.

Application filed February 9, 1915. Serial No. 7,113.

To all whom it may concern:

Be it known that I, JOHN F. HUNT, citizen of the United States, residing at Malden, county of Middlesex, State of Massachusetts, have invented a certain new and useful Improvement in Disinfecting Apparatus, of which the following is a specification, reference being had therein to the accompanying drawings.

10 My invention relates to improvements in toilet disinfecting apparatus and has for its object the production of a new and improved disinfectant holder which is designed to be used in connection with a closet bowl, urinal 15 or the like for the purpose of thoroughly disinfecting, deodorizing or sweetening both the closet and the toilet room.

The device embodying my invention is adapted to be placed within the closet bowl 20 and to cause it to be thoroughly disinfected during each flushing operation, and is so arranged and constructed that during the intervals when the bowl is not being flushed fumes are given off from the disinfectant 25 which serve to purify or disinfect the air in the room in which the holder is located.

Heretofore so far as known to me disinfectant containers have been so designed that a portion of the water is received by them 30 during the flushing operation, and allowed to pass over the disinfectant or other material employed and directly through the container into the bowl. I have found that this does not bring about satisfactory results for 35 the water which thus quickly passes through the container does not become sufficiently impregnated with the material contained therein to thoroughly disinfect and purify the bowl.

40 The device embodying my invention is adapted to hold a portion of the water received during the flushing operation and to partially submerge the material contained in the holder in this water during the intervals 45 while the bowl is not being flushed. The water standing in the container softens and dissolves a portion of the substance contained therein and converts it into a condition to release and so to give off exhalations 50 or volatile substances to disinfect, deodorize, or sweeten the air of the room, and at the same time prepares this portion to be carried down at the succeeding flush into the bowl of the fixture to perform the same 55 duty upon the fixture and its contents, and to still further continue its work on the air

of the room. The substance in the holder thus not only acts upon the air of the room, but it performs its work thoroughly on the fixture and the waste pipe connected therewith, for the portion thus prepared is in a condition to be readily soluble in water, so that when water passes into the container during the next flushing operation and overflows into the bowl, it carries down the prepared portion with it which immediately impregnates or saturates the water in the bowl with the substance employed. When the flushing operation ceases water is again held in the container to act on the disinfectant or other substance employed, and to repeat the operation hereinabove described.

60 A further object of my invention is to so construct the holder that it fits snugly within the bowl beneath the flushing ring and is 65 substantially out of sight and removed from danger of contamination.

A still further object of my invention is to produce a device which is economical, simple, and inexpensive to manufacture, and is 70 devoid of the cumbersome disfiguring structure of most of the devices heretofore produced.

75 My invention will be fully understood from the following description when taken 80 in connection with the accompanying drawings and the novel features thereof will be pointed out and clearly defined in the claim at the close of the specification.

85 In the drawings Figure 1 is a top plan view of a portion of a closet bowl provided with the device embodying my invention. Fig. 2 is a section on line 2—2 of Fig. 1. Fig. 3 is a side elevation of a device embodying my invention. Fig. 4 is an end 90 elevation of the same. Fig. 5 is a longitudinal section of the device. Fig. 6 is a view in perspective of the supporting clip.

95 Having reference to the drawings there is shown at 11 a portion of a closet bowl of 100 common form which is provided with the usual flushing ring 12 having a conduit 13 for water and passages 14 to allow the water to flow down the side of the bowl. Beneath the flushing ring 12 and preferably closely 105 adjacent thereto, a disinfectant holder 15 is located. This is suspended beneath the flushing ring 12 by means of a suitable clip 16 which is shaped to substantially conform 110 to the exterior of the flushing ring, and is provided with an arc shaped supporting portion 17 within which the holder 15 rests.

The lower end of the clip is bent inwardly, as shown at 18, and is adapted to be received within a slot 19 with which the holder 15 is provided. The clip is preferably of spring metal so that the holder may be readily removed when desired, and is so arranged that it retains the holder snugly against the side of the bowl and holds it firmly in position. While I have described at some length the form of supporting means preferred it is obvious that any well known manner of securing the holder in the desired position may be employed.

The holder 15 consists of an open container or vessel 20 of a somewhat tubular shape having sides 21, 22 and ends 23, the sides being curved slightly longitudinally thereof to conform to the horizontal contour of the bowl 11. The ends 23 of the container curve upwardly approximately to the level of the side 21, the bottom 25 and the lower portion of the said sides and ends being imperforate so that the container is adapted to hold water. While any suitable form of solid disinfectant or other material may be employed the holder is particularly designed to retain pencils 24 of disinfectant or other material which are approximately the length of the container bottom 25 and preferably have a curved pencil shape to correspond with the longitudinal curve of the holder. They are held securely in position and are prevented from being displaced during the flushing operations by the ends 23 and by curved lateral extensions 26, 27, and 28, which are integral with the side 22 and project over toward the side 21. The lateral extensions further serve to provide contacts for the holder against the bottom 40 of the flushing ring 12 to enable the supporting clip to retain the holder firmly in place. A portion of the center extension 27 together with a portion of the sides and bottom also affords the necessary surface for the grip of the supporting clip.

While I have described pencils of disinfectant or the like as being particularly adapted to be used in my device it is obvious that other forms of disinfecting, de-odorizing or sweetening material may be employed.

It will be noted that the holder 15 is so constructed that when supported by the clip 16 as shown in Figs. 1 and 2 it is directly beneath the passages 14 in the flushing ring

12 of the bowl. When thus suspended water passes from the flushing ring 12 through the passages 14, by the extensions 26, 27 and 28, and directly into the container 15, the extensions being so arranged that the water can freely flow into the container and overflow into the bowl. The container therefore is practically an open vessel to and from which the water may readily flow. A portion of the material in the water which remains in the container after a flushing operation is softened by the action of the water in which it stands and is prepared to be carried down into the bowl by the water flowing into the container during the succeeding flushing operation.

I prefer to retain only a small amount of water in the container so that the solution obtained by the dissolving material may be sufficiently strong to act thoroughly on the bowl and give off the required fumes into the room. For this purpose I provide drain notches 29 at each end of the upper edge of the holding portion of the container which notches are arranged to allow only a relatively small amount of water to remain in the bottom thereof.

I regard my invention as important for it embodies a device, which is practical, simple, economical, and inexpensive to produce and which may be readily installed in a closet bowl so that it is substantially out of sight. Furthermore it provides means for keeping the solid disinfecting, deodorizing or sweetening material in a predetermined small quantity of water between flushings thereby affording a proper quantity of strong solution to act upon the bowl at the next flushing and during the interim to send off exhalations into the room.

What I claim is:

A disinfecting device consisting of a receptacle adapted to contain disinfecting material and having an imperforate bottom with upwardly curved ends, and a partly open top provided with overhanging extensions, combined with means for detachably securing said receptacle to the underside of the rim of a closet bowl.

In testimony whereof I affix my signature, in presence of two witnesses.

JOHN F. HUNT.
